HELICAL SPRING ACTUATED SLIDING SIDE JAW WRENCH

Filed Jan. 10, 1947

UNITED STATES PATENT OFFICE

2,447,094

HELICAL SPRING ACTUATED SLIDING SIDE
JAW WRENCHRoyal H. Schlotz, Milwaukee, Wis., assignor to
G. F. Schlotz & Company, Inc., Milwaukee,
Wis., a corporation of Wisconsin

Application January 10, 1947, Serial No. 721,306

6 Claims. (Cl. 81—165)

1

This invention relates to an improved construction of wrench of the type comprising a fixed and a slidably mounted jaw and that more particularly has reference to a novel means of simple construction for actuating the sliding jaw and for effectively maintaining the actuating means in any position to which it is manually moved whereby said actuating means will function to retain the sliding jaw in any adjusted position.

More particularly, it is an object of the invention to provide a sliding jaw actuator for wrenches including worm and pinion means and an actuator therefor in the form of a resilient helix, the resiliency of which will function in a unique manner for maintaining the parts in any position to which they are manually moved.

Still a further object of the invention is to provide a wrench of extremely simple construction capable of being readily assembled or disassembled and provided with adjustable bearing means for varying the resiliency of the helical actuator for thereby varying the extent to which it will function for maintaining the parts in adjusted position.

Still a further object of the invention is to provide a wrench having a tubular dust or dirt guard which is so constructed that it will substantially eliminate any noise incident to the operation of the parts occurring during adjustment of the wrench and at the same time lighten the wrench and reduce the cost of manufacture thereof.

Various other objects and advantages of the invention will hereinafter become more fully apparent from the following description of the drawing, illustrating a preferred embodiment of the invention, and wherein:

Figure 1 is a side elevational view, partly in section, of a wrench constructed in accordance with the invention;

Figure 2 is an edge view in elevation thereof looking from left to right of Figure 1;

Figure 3 is a cross sectional view taken substantially along a plane as indicated by the line 3—3 of Figure 1;

Figure 4 is a fragmentary longitudinal sectional view taken substantially along a plane as indicated by the line 4—4 of Figure 2;

Figure 5 is a side elevational view of a portion of the wrench, and

Figure 6 is a side elevational view of another portion thereof.

Referring more specifically to the drawing, the improved wrench in its entirety is designated generally 7 and is capable of being formed of any suitable metal and includes an enlarged head 8

2

having a stationary jaw 10 and an integral shank or handle portion 9 extending from a part of the head 8 and remote from the stationary jaw 10.

The head 8, as best seen in Figure 4, is recessed in a direction generally diagonally of the longitudinal axis of the wrench 7, said recess including a guide portion 11 which opens outwardly of the arcuate edge of the head 8 at diametrically opposite points, and an inner recessed portion 12 which is disposed substantially parallel to the guide portion 11 and between said portion and the handle or shank 9. As seen in Figure 4, the adjacent portions of the recessed portions 11 and 12 are disposed in communication, for a purpose which will hereinafter become apparent. The inner recessed portion 12 is provided at its upper end with an inwardly opening, substantially conical shaped bearing recess 13 and has an enlarged, internally threaded opposite end 14.

The guide recess 11 is provided on opposite sides thereof with arcuate grooves 15 for receiving and slidably engaging correspondingly shaped ribs 16 of an elongated shank portion 17 of an adjustable jaw 18. The elongated shank portion 17 is slidably disposed in the guide 11 for mounting the movable jaw 18 in opposed relationship to the fixed jaw 10 and for movement toward and away from said jaw 10.

A worm 19 is disposed longitudinally in the recessed portion 12 and is provided with a conical shaped shank end 20 which is journaled in the bearing recess 13, said worm having an opposite tapered end 21 which is journaled in a similarly shaped, inwardly opening bearing recess 22 of a threaded plug or closure 23 which is detachably mounted in the internally threaded end 14 of said recessed portion 12. The flange 17 of the movable jaw 18 is provided with an enlarged inner edge portion 24 which is toothed to engage with the helical thread of the worm 19 whereby said jaw 18 will be actuated and moved either toward or away from the jaw 10 when the worm 19 is revolved.

The handle or shank 9 is provided with a bore 25 extending from end to end thereof and having an internally threaded outer end 25¹. As best seen in Figure 3, the bore 25 is circular in cross section but the handle or shank 9 is substantially oval-shaped in cross section, externally thereof.

Referring particularly to Figure 5, a tube of hardened or tempered spring steel is provided with a helical slot extending substantially from end to end thereof and forming a plurality of convolutions and by means of which the tube is converted into a helical spring 26 composed of a plu-

rality of relatively wide convolutions 27 having spaced adjacent edges forming a helical slot 28 therebetween. The slot 28 may extend entirely to the ends of the tube from which the helical spring 26 is formed or to points adjacent said ends. A pinion 29 is provided with a restricted shank portion 30 which is suitably secured in one end of the spring 26 for supporting the pinion 29 in outwardly projecting relationship to said end and keyed thereto. The spring 26 is inserted in the bore 25 and extends substantially from end to end thereof, as indicated in broken lines in Figure 1. As seen in Figure 4, the head 8 is provided with an integral projection 31 which overlies a portion of the inner end of the bore 25 and which is provided with a tapered projection 32 which extends into a recess 33 in the outer end of the pinion 29 for journaling said pinion and the adjacent end of the spring 26 within the bore 25 and substantially axially thereof. The pinion 29 has a portion thereof extending through a communicating opening 34 into the recessed portion 12 to mesh with a pinion 35 which is keyed to the worm 19.

An externally threaded plug or closure 36 is detachably mounted in the threaded outer end 25¹ of the bore 25 and is provided at its inner end with a restricted projection 37 which extends into the opposite, outer end of the spring 26 to provide a journal for said end. The enlarged head of the outer end of the closure or plug 36 is provided with a substantially V-shaped bail 38 to provide means for hanging the wrench 7 and for turning the closure or plug 36 for applying and removing the same and also for adjustably positioning it in the threaded portion 26, for a purpose which will hereinafter become apparent.

A collar 39, shaped to correspond to the oval external shape of the handle or shank 9, is slidably mounted thereon and has a threaded opening 40 for receiving the outer enlarged threaded end 41 of a pin 42 which extends inwardly through a slot 43 in the handle or shank 9. The slot 43 is disposed longitudinally of the handle or shank 9 and extends substantially from end to end thereof and the pin 42 extends therethrough and into a portion of the helical slot 28 of the helical spring 26.

A tubular dust guard 44 is disposed in the bore 25 and around the helical spring 26 and extends substantially from end to end thereof. The dust guard 44 is provided with a spiral slot 45 which extends substantially from end to end thereof and which makes approximately one complete revolution of the tube. The guard 44 provides means for substantially closing the slot 43 to prevent dust or dirt from entering the bore 25 therethrough and the pin 42 extends through the slot 45 thereof and causes the guard 44 to revolve slowly as the collar 39 is moved longitudinally of the shank 9 so that the portion of the slot 45, which is at any time in engagement with the pin 42, will also be in registry with the slot 43.

Assuming that the wrench 7 is assembled as illustrated in Figure 1, by sliding the collar 39 on the shank or handle 9 toward the head 8, the pin 42 will be caused to ride in the slot 28 for causing the helical spring 26 to rotate in a counterclockwise direction, looking downwardly thereon, for thereby revolving the pinion 29 in the same direction to move the pinion 35 which is enmeshed therewith and the worm 19 in a clockwise direction for moving the jaw 18 toward the fixed jaw 10. Likewise, if the collar 39 is moved away from

the head 8, the parts will be revolved in the opposite direction for moving the jaw 18 away from the jaw 10. The convolutions 27 are so arranged that the helical slot 28 closely engages with the pin 42. Accordingly, when the collar 39 is moved in one direction the convolutions 27 disposed between the pin 42 and the end of the spring 26, toward which the collar 39 is being moved, will be caused to yield to permit the portion of the convolutions of the slot 28, engaged by the pin 42, to be spread sufficiently to permit the pin to ride therein. As a result, when pressure is relieved from the collar or slide 39 the convolutions 27 will return by their own resiliency to their normal position for clamping the pin 42 between two of the convolutions and with sufficient gripping force so that the movable jaw 18 will be effectively locked in its adjusted position until manual pressure is again applied to the collar or slide 39. As the projection 37 forms one bearing of spring 26, the plug 36 can be adjusted in the bore portion 25 to vary the tension of spring 26.

The guard sleeve 44 functions in a conventional manner for protecting the bore 25 of the handle or shank 9 from dust or dirt. However, such sleeves are conventionally formed of metal, usually brass, whereas the sleeve 44 is formed of a plastic material, preferably cellulose acetate butyrate. By providing the sleeve 44 of a plastic material the weight and cost of production thereof is considerably reduced and the operation of the wrench is rendered substantially silent as the plastic guard sleeve 44 deadens the sound of the movement of the parts incident to the adjustment of the movable jaw 18.

Various modifications and changes are contemplated and may obviously be resorted to, without departing from the spirit and scope of the invention as hereinafter defined by the appended claims.

I claim as my invention:

1. In a wrench of the character described, a wrench head provided with a fixed jaw and having a recessed portion, a movable jaw having a shank portion slidably disposed in the recessed portion of the wrench head, worm means journalled in the recessed portion of the head for cooperating with a portion of the shank of the movable jaw for moving said movable jaw relatively to the head when said worm means is revolved, an elongated tubular handle projecting from a part of the wrench head and provided with a longitudinally disposed slot, a helical spring journalled in said tubular handle, pinion means connecting the helical spring to said worm means, a collar slidably disposed on the handle and having a pin extending through the slot thereof and engaging the slot formed by the spaced convolutions of the helical spring, said collar being slidable on the handle for rotating the helical spring to actuate the movable jaw, and said pin being normally clamped between the convolutions of the spring by the resiliency thereof for retaining the parts in adjusted positions.

2. A wrench as in claim 1, bearings for journaling said helical spring in the tubular handle, and one of said bearings being adjustable relatively to the handle for varying the resiliency of the convolutions of the spring.

3. A wrench as in claim 1, said helical spring comprising a tube of tempered spring steel having a helical slot cut therein, substantially from end to end thereof.

4. A wrench as in claim 1, said tubular handle having a bore of substantially circular cross section and being non-circular externally in cross section, and said collar being shaped to closely engage the handle and being slidably and non-rotatably disposed thereon.

5. A wrench as in claim 1, the recess of said wrench head having an internally threaded open end portion, and a threaded member engaging said threaded portion and having a bearing for journalling one end of the worm means for detachably mounting the worm means in the wrench head.

6. In a wrench of the character described, a wrench head provided with a fixed jaw and having a recessed portion, a movable jaw having a shank portion slidably disposed in the recessed portion of the wrench head, worm means journalled in the recessed portion of the head for cooperating with a portion of the shank of the movable jaw for moving said movable jaw relatively to the head when said worm means is revolved, an elongated tubular handle projecting from a part of the wrench head and provided with a longitudinally disposed slot, a helical spring journalled in said tubular handle, pinion means connecting the

helical spring to said worm means, a collar slidably disposed on the handle and having a pin extending through the slot thereof and engaging the slot formed by the spaced convolutions of the helical spring, said collar being slidable on the handle for rotating the helical spring to actuate the movable jaw, said pin being normally clamped between the convolutions of the spring by the resiliency thereof for retaining the parts in adjusted positions, and a dust guard tube journaled in the tubular handle and rotatably disposed around the helical spring, said tube having a helical slot extending substantially from end to end thereof and in which the pin is slidably disposed.
